UNITED STATES PATENT OFFICE.

CHARLES E. BUELL, OF NORTH PLAINFIELD, NEW JERSEY, ASSIGNOR TO GENERAL FIRE EXTINGUISHER COMPANY, OF NEW YORK, N. Y., A CORPORATION OF NEW YORK.

Fire-Extinguishing Apparatus.

No. 909,985

Specification of Letters Patent. Patented Jan. 19, 1909.

Application filed August 2, 1897. Serial No. 646,847.

To all whom it may concern:

Be it known that I, CHARLES E. BUELL, of North Plainfield, Somerset county, State of New Jersey, have invented Improvements in 5 Fire-Extinguishing Apparatus, of which the following is a specification.

My invention consists in certain combinations and subcombinations to be hereinafter described.

10 In the accompanying drawings Figure 1 shows a combined valve mechanism and alarm apparatus with a main valve adapted to automatically admit water to a system of pipes when a sprinkler opens, and a sprinkler 15 adapted to be made operative by the action of heat for carrying out my invention. Fig. 2 shows a modification.

Referring to Fig. 1 there is shown the main supply pipe M leading to a source of 20 water supply and connecting with the valve S V and through said valve with the automatically operated main valve for admitting water to the system of pipes when a sprinkler is opened by heat, comprising the valve V V' 25 and then connecting with the valve R V which is placed intermediate between the said main valve and the main riser R. The main riser valve R V is not essential to the 30 operation of a system, but is a very convenient feature in the apparatus when resetting the same. The valve S V comprises a valve v for controlling the water-way between the supply main and the sprinkler system, and a valve v' which is adapted to 35 close a vent pipe or outlet v c so that when the valve v is in position to open the water-way between the supply main and the system, the valve v' is held to close the outlet v c. The object of this arrangement is to 40 admit of venting that part of the valve mechanism located between the main supply valve S V and the automatically operated valve V', when the said valve S V is moved to close, or to partly close, the water-way 45 between the source of water supply and the system of sprinklers. The effect of venting this part of the apparatus is to make operative the pressure indicator I by relieving the pressure in the same and thereby causing 50 its hand h to move into contact with the terminal of a wire g, which is insulated from said indicator forming a part of an electric circuit for making operative the alarm apparatus E consisting of an ordinary annun- 55 ciator having its drop d interlocking with

its armature lever a which is adapted to be made operative by the attraction of its armature, thereby releasing the drop d, and through the operation of that device to bring into operation the bell or gong B in a well known way. By this means the opening of a sprinkler by the heat of a fire, or the turning of the main supply valve from its position of fully open, will be denoted by the bringing into action of the alarm apparatus E and gong B. A similar result is provided for if the valve R V is turned to close the water way; but instead of making operative a pressure indicator the turning of the valve stem closes a normally open branch by allowing spring e' to pass off of the insulating block g and close the circuit over wire w' and the pipes of the system to sound the alarm.

In Fig. 2 there is shown a connecting device for connecting the terminals of a closed circuit to an ordinary main valve in a manner to produce an alarm if the valve is turned from its position of being open, by removing the supporting pin which holds the spring e' in contact with the stop c, and by so doing causes the connected circuit to be opened and a suitable alarm apparatus in connection therewith to indicate and announce the said closing or partial closing of the water-way in said valve. The pin c² is easily secured to a valve wheel v w by means of a screw threaded pin screwed into a hole in the said wheel. In the position of open, as shown, the pin forces the spring e' against stop c from which it is insulated by block b. When now the wheel is turned so that the pin c² passes away from under the spring e' the alarm is made operative by opening the circuit. It is obvious that with slight change the closing of a normally open circuit would be effected by the movement of wheel v w. With a support s² adapted to be bolted on to a valve already in place, an alarm can be added to such valve mechanisms as are now installed.

Referring again to Fig. 1 there is shown a main valve V held to normally close the water-way between valve S V and valve R V by entrapped water forcing valve V over the outlet k in casing C and through valve stem v s, forcing valve V' against its seat. The entrapped water enters the casing C through pipe m which is located so as to enter main M between valve S V and the source of water supply, which location is

essential to the use of the apparatus. An automatically operated vent v has connection between the casing C and the main riser R and consists of a diaphragm in a metal case carrying a plate or valve for normally closing the vent v when air pressure from the riser enters the metal case, pressing outward the diaphragm. The discharge of the air from the riser by the opening of a sprinkler allows the water pressure in the casing C to be relieved, and the valve V is lifted by the pressure against valve V', and instantly the entrapped water in casing C pours out of the opening k which was held closed by valve V. The discharge of pressure from casing C causes an alarm to be indicated and announced by the removal of pressure on the gage G which, like indicator I, makes operative an electric circuit over an insulated wire contained in tube t and formed and completed by the pipe t and the metal apparatus comprising the valvular mechanism and the pipe t . The indicator or gage I acts independent of the gage G, but both of said gages act to make operative the annunciator E and bell connected thereto, the gages serving to denote a distant alarm for each by a visual signal, and a notifying signal common to both is provided by the annunciator and bell. The pressure gage G is provided with an insulated stop g that is a terminal of the insulated wire in the tube t , and the hand on the gage G is the terminal of the return portion of the electric circuit that includes the alarm apparatus E, and by a lowering of the pressure in casing C the hand h of gage G comes into contact with the insulated stop g and makes operative the alarm. A manually operated vent f^s is provided for venting casing C when it is desired to test the valves V V' without admitting water to the sprinkler pipes or discharging air therefrom; which is readily accomplished by temporarily closing the valves S V and R V as the vent f^s is opened. A vent or drip f and f^2 can be used with advantage as shown for dripping the system when it becomes desirable to do so. The pipe m^2 leads to an air compressor. By the employment of a pressure indicator and conducting wire or wires within a tube stoppered to exclude the entrance of water, an apparatus for indicating and announcing the closing of the water-way from a source of supply to a system of sprinklers is afforded which is not readily reached to be accidentally or purposely put out of order, as the apparatus can be located in the office where it will be protected and the moving part of the indicator, the terminal contact, and the conductors are inclosed; the hand h and contact g being covered by glass and thus protected so that to displace them the glass must be removed or broken.

Although the wire from indicator I is

shown simply by dotted line it is intended to inclose it as a connected conductor to gage G. All conductors for such purpose can be inclosed.

The advantages of the combined alarm and valve mechanism are that the valve which controls the water-way between a sprinkler system and the source of water supply cannot be left closed without the fact being known, due to the continued ringing of the alarm, and the complete failure of the system thereby avoided, a failure which is not uncommon and which can only be prevented from occurring by a detector that is brought into action by the movement of the valve itself from the position of open.

The advantages of such an automatic main valve as is herein shown and described are those of simplicity of construction, the quickness of its operation, the ease of testing the same without discharging the air or filling the system with water.

What I claim is:

1. The combination with an automatic sprinkler system of the valve V V' consisting of the valve V' held to its seat by entrapped water upon valve V and provided with an automatically operated vent, a valve S V normally open in the water-way between the valve V and the source of water supply, and an electro mechanical alarm apparatus adapted to be made operative by the turning of the valve S V from a position of open, substantially as set forth.

2. A valve mechanism comprising the valve controlling the water-way between a source of water supply and a system of automatic sprinklers that is normally open, a thermally operated valve normally closing said water-way, alarm apparatus in operative relation to said valves which is adapted to give an alarm signal by the moving of the first named valve to close said water-way, and by the moving of the last named valve to open said water-way, substantially as set forth.

3. The combination with the pipes of a sprinkler system of an alarm apparatus having connection through pressure actuated mechanism to the pipes of said system and adapted to produce an alarm when the pressure in said pipes is varied by the opening of a sprinkler, a main supply valve that is normally in the position of fully open and is provided with means for making operative the said alarm apparatus when the said main valve is turned from the position of fully open, substantially as set forth.

4. A sprinkler system, a dry pipe valve normally retaining an air pressure in said system, a main supply valve that is normally in the position of fully open to admit water to said system, connections from said dry pipe valve and said main supply valve to an electric circuit for making operative an

alarm apparatus to denote the opening of a sprinkler and to denote the turning of said supply valve from the position of fully open, substantially as set forth.

5. The combination, with an automatic sprinkler system, of a main supply valve normally open, a second valve located between said main supply valve and the distributing pipes of the system and arranged to be oper-

ated by a reduction of pressure in the system, 10 and means for sounding an alarm when either of said valves is moved from its normal position, substantially as set forth.
